UNITED STATES PATENT OFFICE.

GEORGE W. SMITH, OF ROCKFORD, ILLINOIS, ASSIGNOR TO THE INGERSOLL MILLING MACHINE COMPANY, OF ROCKFORD, ILLINOIS. A CORPORATION OF ILLINOIS.

MILLING-MACHINE.

1,094,940.

Specification of Letters Patent. Patented Apr. 28, 1914.

Application filed September 30, 1911. Serial No. 652,205.

To all whom it may concern:

Be it known that I, GEORGE W. SMITH, a citizen of the United States, residing at Rockford, in the county of Winnebago and State of Illinois, have invented certain new and useful Improvements in Milling-Machines, of which the following is a specification.

The object of this invention is to drive the cutter holding bar from both ends in order that the torsion strain may be removed.

In the accompanying drawings, Figure 1 is a face elevation of a milling machine containing my improvements, in which sections 15 of the casing are broken away to show the gear drive. Fig. 2 is an end elevation. Fig. 3 is a section on line *a a* Fig. 2. Fig. 4 is a section on line *d d* Fig. 3. Fig. 5 is a section on line *c c* Fig. 3. Fig. 6 is a section 20 on line *b b* Fig. 3. Fig. 7 is a section on line *e e* Fig. 8. Fig. 8 is a section on line *f f* Fig. 7. Fig. 9 is a section on line *g g* Fig. 7. Fig. 10 is an elevation of the adjustable connection between the section of the drive 25 shaft, in which one-half is in section. Fig. 11 is an end view of Fig. 10.

The operative parts of the milling machine are supported by the base 1 which also supports a work holding table 2. A main 30 drive shaft is in two sections 3 and 4 supported in bearings 5. These sections are connected by a coupling in two sections 6 and 7 each formed with a serrated face. The section 7 is formed with slot 8 through which 35 screws 9 pass into the other section 6, by means of which the two sections are clamped together. The section 6 is connected to the shaft section 3 by the key 10, and the section 7 is connected to the shaft section 4 by 40 the key 11. To the shaft section 3 is connected a spur-gear 12 and to the shaft section 4 is connected a spur-gear 13.

The short intermediate shafts 14 and 15 are supported by the casings 16 and the 45 shaft 14 supports two spur-gears 17 and 18. The spur-gear 17 meshes with the spur-gear 12. The shaft 15 supports two spur-gears 19 and 20, and the spur-gear 19 meshes with the spur-gear 13.

50 The casings 16 support two rotatable sleeves 21 or members for holding cutting means, to each of which is keyed a spur-gear 22 which mesh with the spur-gears 18 and 20. These gears 22 are held against bodily

displacement by the casings 16 as shown at 55 Fig. 3, in order that the sleeves 21 can move endwise through it, and since the construction of both said casings and operative parts inclosed therein is similar, I have deemed it only necessary to show in section, 60 one of them as in Fig. 3, and also describe the construction and operation of same. Around this sleeve 21 is located a collar 23 provided with a rack 24 with which a pinion 25 meshes. This pinion is rotated by a 65 wrench applied to the projecting end 26 of the shank of the gear 25. The collar 23 is located between the rim 27 formed a part of the sleeve 21, and the ring 28 having a screw-threaded connection with the end of 70 the sleeve. The inner end of the sleeve 21 is formed with a transverse rectangular slot 29 from the bottom of which extends a tapered recess 30. The sleeve 21 is formed with an opening 31 extending through its 75 length. A removable socket block is provided with a conical end 32 fitted to the recess 30, and with a rectangular end 33 fitted to the rectangular slot 29. This removable socket block has a square opening 34 80 through it.

A cutter holding bar 35 is provided with a key-way 36, and the ends of this bar are square to be received in the square openings 34 in the removable socket blocks. A center support 37 is provided for the cutter holding bar 35, and to the cutter bar are connected cutters 38. The sleeves 21 are withdrawn sufficiently to allow of the positioning of the cutter holding bar between 85 them, they are then moved inward until the square ends of the cutter bar are received in the square openings of the removable socket blocks. The cutter holding bar is rotated from both ends by the gear connection with the sectional drive-shaft. By 90 means of the adjustable connection between the sections of the drive-shaft the slack in the teeth of the gearing can be overcome so that both ends of the cutter holding bar may 95 be positively rotated without torsional strain. To the section 3 of the drive shaft is connected a spur gear 39 which is rotated by a gear connection with a motor 40.

I claim as my invention.

1. In apparatus of the character set forth, the combination of two rotatable cutter holding members, of common driving means in

connection with both of said cutter holding members for positively driving same, and means included in said driving means for allowing adjustable axial movement of one of said cutter holding members relative to the other.

2. In apparatus of the character set forth, the combination with a rotary cutter holding bar, of a driving shaft comprising sections, separate sets of gearing extending from the respective sections of the driving shaft to the respective ends of the bar for positively driving the latter at both ends, and means for positively but adjustably securing the driving shaft sections together, and against relative movement, to secure an equal transmission of power through the sets of gear.

3. In apparatus of the character set forth, the combination with a rotary cutter holding bar, of a driving shaft comprising sections, separate sets of gearing extending from the respective sections of the driving shaft to the respective ends of the bar for positively driving the latter at both ends, said driving shaft sections being relatively rotatable and having interlocking serrated heads at their adjacent ends, and means for positively locking the heads together to prevent the relative rotation of the sections.

4. In apparatus of the character set forth the combination with two rotatable cutter holding members, of a drive-shaft, a driving connection between said drive-shaft and each cutter holding member, and means included in the said drive between said cutter mem-

bers for allowing adjustable axial movement of one cutter member relative to the other.

5. In apparatus of the character set forth, the combination with a single rotary cutter holding bar, of a driving shaft comprising relatively rotatable sections, a set of gearing connecting one of the driving shaft sections with one end portion of the cutter holding bar, a corresponding set of gearing connecting the other driving shaft section with the other end portion of the cutter holding bar, said sets of gearing positively driving the latter, a connection between the driving shaft sections for permitting their relative adjustments, but normally holding them positively against relative rotation, and a motor geared to the driving shaft between the sets of gears.

6. In apparatus of the character set forth, the combination of a rotary cutter holding bar, two rotatable members respectively connected to opposite ends of the cutter holding bar, a driving connection for positively driving said rotatable members, and means included in said driving connection for allowing adjustable axial movement of one of said rotatable members relative to the other.

In testimony whereof I have hereunto set my hand in presence of two subscribing witnesses.

GEORGE W. SMITH.
